UNITED STATES PATENT OFFICE.

RUBEN B. LAWRENCE, OF BELLEVUE, PENNSYLVANIA, ASSIGNOR TO FEDERAL LABORATORIES, INCORPORATED, OF PITTSBURGH, PENNSYLVANIA, A CORPORATION OF DELAWARE.

ARTICLE-CARRYING CONTAINER.

Application filed June 21, 1922. Serial No. 569,824.

To all whom it may concern:

Be it known that I, RUBEN B. LAWRENCE, a citizen of the United States, residing at Bellevue, in the county of Allegheny and

5 State of Pennsylvania, have invented a new and useful Improvement in Article-Carrying Containers, of which the following is a full, clear, and exact description.

The present invention relates to article 10 carrying containers, and more particularly to containers for carrying valuable goods, such, for example, as a handbag carried by a bank messenger.

The article carrying container is provided 15 with a device for emitting incapacitating gas which will be set in operation in case of holdup. The incapacitating gas will prevent any person from carrying away the article carrying container, thus completely 20 foiling any robber who hopes to carry away his loot. An incapacitating gas may be used which will completely incapacitate any person in the immediate vicinity but which will be leave no permanent injurious effects. 25 Robbery can thus be more surely prevented than by the messenger carrying a revolver, and at the same time the lives of innocent bystanders will not be imperiled.

In the drawings which illustrate the preferred embodiment of the invention,—

Figure 1 is a side elevation of a handbag, the gas emitting device being dotted in;

Figure 2 is a side elevation of the gas emitting device removed from the handbag;

Figure 3 is a central vertical section through the gas emitting device;

Figure 4 is a detail view of the cord and safety knot;

40 Figure 5 is a section along the line V—V of Figure 2;

Figure 6 is a section along the line VI—VI of Figure 3.

Referring to the embodiment of the in-

45 vention illustrated in the drawings, the invention is illustrated as embodied in an ordinary handbag 1 such as is commonly used by bank messengers or other persons for carrying large amounts of currency. The gas emitting device, indicated generally by the

50 reference character 2, is mounted inside of the bag and is actuated by means of a cord 3 which extends through a bushing 4 on the side of the bag adjacent to the bag handle

5. The cord 3 is fastened to one end of the handle so that it may be conveniently grasped by the carrier and pulled to set off the gas in case robbery is attempted.

The gas emitting or generating device 2 consists of a cylindrical shell 6 secured by 60 suitable straps 7 in the handbag. Inside of the shell 6 and spaced from its walls, is a renewable gas cartridge having a foraminous holder 8 which contains the gas producing substance 13. A mixture of chloroacetophenone crystals and gunpowder is preferably employed. The gunpowder upon ignition by its heat vaporizes the chloroacetophenone crystals into a gas. The gunpowder, by its combustion furnishes a large 70 volume of vehicular gas which is emitted from the bag, carrying with it the chloroacetophenone gas. The chloroacetophenone gas is a lachrymose gas which has a practically instantaneous effect and for a space 75 of several minutes will completely incapacitate the person who is gassed. A would-be robber's attention will be entirely devoted to getting away from the immediate vicinity the best he can without thought of 80 carrying away the gas emitting bag. The gunpowder may be either ordinary black powder or smokeless powder. If smokeless powder is used, it is preferred to mix with it a small amount of some inert combustion 85 retarding material, such as magnesium oxide, to make the powder more slow burning.

A short tube or nipple 9 extends from the shell 6 through the bag for the escape 90 of the gas.

The gas cartridge is preferably spaced apart from the walls of the shell 6, because I have found that the combustion takes place better and more completely if 95 the mass of gas producing crystals and gunpowder is substantially surrounded by an air pocket. The gas producing crystals and gunpowder are preferably melted into a solid or sintered cake by heating to the 100 temperature of boiling water, so that loose material will not rattle through the holes of the holder 8. The crystals and gunpowder may also be caked together by moistening them with some solvent such as benzene.

The term "gunpowder" as here employed is intended as a term of general definition

and not of limitation, and to include various kinds of gunpowder or similar materials which are capable of self-supporting combustion in the absence of an adequate supply of oxygen and produce a volume of gas.

The gas is set off by means of a detonating cap struck by a hammer and which is released by the cord 3. As shown in the drawings, an ordinary shotgun cartridge shell 10 is fitted over one end of the holder 8. This shell is provided with the usual cap 11 filled with fulminate of mercury or similar detonating material. A primer, such as ordinary black powder or "meal powder" 12 is provided next to the cap 11 to be ignited thereby and in turn ignite the mixture of gunpowder and crystals 13.

The cap 11 is arranged to be struck by a hammer 14. The hammer 14 is carried on the end of a rod 15 set in a cylinder 16 and provided with a coil spring 17. The rod 15 has a latch-piece 18 which is normally turned in the position shown in Figures 3 and 6 to hold the hammer 14 retracted. When the cord 3 is pulled, the latch-piece 18 is turned to enter the slot 19 and permit the spring 17 to drive the hammer against the cap 11.

The cord 3 extends through a tube 20 the distal end of which projects through the back near the handle. The end of the tube 20 has a bushing or cap 4. The cord 3 at the distal end of the tube has a knot 22 which is large enough so that it cannot pass through the cord opening in the cap 4. If the cap 4 is screwed on the end of the tube 20 the cord cannot be pulled to release the hammer 14, and the bag can be carried without any particular precaution in case the safety device or cap 4 is screwed in place. When, however, the bag is filled with currency and is being carried through the streets, the cap 4 may be unscrewed and the bank messenger can then, by a simple pulling movement of the cord 3, set the gas emitting device into instant operation. Since the cord 3 is next to the handle, it can be pulled and the gassing device set in operation when the bank messenger drops the bag in case he is ordered to hold up his hands, or can be easily and naturally pulled in case a person attempts to grab the bag out of the messenger's hands.

No person would be able to pick up the bag and carry it off for some time after the gassing device is set off, so that the bag cannot be stolen until it is time for police or other help to arrive and frustrate the attempted robbery.

After the device is used, it can be easily and immediately refilled with another charge of gas producing material. For this purpose, the shell 6 can be readily taken apart. The cap 23 which covers the latch-

piece and which carries the tube 20, is held by a bayonet joint 24. The sleeve 25 in which is mounted the cartridge shell 10 which holds the gas cartridge, is secured to the body of the shell 2 by means of a bayonet joint 26. The cylinder 16 which holds the hammer mechanism is held to the sleeve 25 by means of a bayonet joint 27 and can be thus easily separated from it to insert another gas cartridge. The cartridge is held in place by the engagement of the edge 28 of the shell between the end of the cylinder 16 and the sleeve 25. The joint between the sleeve 25 and the shell 6 tightly closes this end of the gas chamber. The other end is closed by the cap 29. A thin plug of paraffin 30, which is readily blown out by the pressure of the gas, seals the opening through the tube 9.

While I prefer to generate the incapacitating gas by the combustion of gunpowder associated with the gas forming material, it is obvious that the gas might be otherwise generated. Moreover, the gas emitting device may be employed with article carrying containers other than handbags. For example, it may be employed in larger receptacles carrying valuable freight, and may be set in operation automatically if the receptacle is forced open. It is to be understood, therefore, that the present invention is not limited to its illustrated embodiment but may be otherwise embodied within the scope of the following claims.

I claim:

1. The combination with a container adapted for transporting articles of a gas-emitting device for protecting the container and its contents against robbery, the gas-emitting device being adapted to continue to emit an incapacitating gas over a substantial period of time after being once set in action, and means for setting the device into action, said means comprising a member adapted to be grasped by the carrier of the container and arranged to set the gas-emitting means into operation when the member is actuated by the carrier, substantially as described.

2. The combination with a container adapted for transporting articles, of a device for protecting the container and its contents against robbery, comprising gas-emitting means adapted to continue to emit an incapacitating gas over a substantial period of time after being once set in action, means for setting said gas-emitting means in action upon attempted theft or robbery of the container, and a chamber for holding the gas emitting means and maintaining it separate from the container, the chamber having an opening outside the container, substantially as described.

3. The combination with a container adapted for transporting articles, of a cham-

ber separate from the container, gas emitting means therein adapted to continue to emit an incapacitating gas after being once set in action, manually controlled means for setting the gas emitting means in action, and a gas outlet leading from the chamber to a point outside the container, substantially as described.

4. The combination with a container adapted for transporting articles, of a chamber within the container but separated therefrom, gas emitting means within the chamber adapted to continue to emit an incapacitating gas after being once set in action, manually controlled means for setting the gas emitting means in action, and a conduit leading from the chamber to a point outside the container, the conduit being relatively small in cross sectional area, substantially as described.

5. The combination with a container having a handle and adapted for transporting articles, of a device for protecting the container and its contents against robbery, the device being adapted to emit an incapacitating gas, manually controlled means for actuating said device and means for rendering the actuating means inoperative when desired, substantially as described.

30 6. The combination with an article carrying container, of a device for emitting an incapacitating gas, comprising a container holding an incapacitating gas producing

substance and a material capable of self-supporting combustion associated with the gas producing substance to heat and vaporize it, and manually operable means for igniting such material, substantially as described.

7. The combination with an article carrying container, of a device for emitting an incapacitating gas, comprising a container holding a vaporizable solid incapacitating gas producing substance and gunpowder, a detonating cap for igniting the gunpowder, a hammer for striking the cap, and manually operable means for releasing the hammer, substantially as described.

8. The combination with an article carrying container having a handle, of a device for emitting an incapacitating gas, comprising a container within the article carrying container holding a solid vaporizable incapacitating gas producing substance and gunpowder, a cap for igniting the gunpowder, a hammer for striking the cap, and manually operable means for releasing the hammer including a cord extending through the wall of the article carrying container adjacent to the handle to be readily grasped and pulled by the person carrying the article carrying container, substantially as described.

In testimony whereof I have hereunto set my hand.

RUBEN B. LAWRENCE.
